E. McGRAW.
DETACHABLE DOOR EXTENSION,
APPLICATION FILED JAN. 19, 1917.

1,253,618.

Patented Jan. 15, 1918.

UNITED STATES PATENT OFFICE.

EDWIN McGRAW, OF MILTON, INDIANA.

DETACHABLE DOOR EXTENSION.

1,253,618.

Specification of Letters Patent. Patented Jan. 15, 1918.

Application filed January 19, 1917. Serial No. 143,206.

To all whom it may concern:

Be it known that I, EDWIN McGRAW, a citizen of the United States, residing in the town of Milton, in the county of Wayne 5 and State of Indiana, have invented a new and useful Detachable Door Extension, of which the following is a full, clear, and comprehensive specification and exposition, the same being such as will enable others

10 to make and use the same with exactitude.

The object of my invention, broadly stated, is to provide a detachable door-extension particularly intended to be employed in connection with automobiles, or other vehicles, the same to be employed in connection with one or more of the doors thereof.

It is well known that when the side curtains of a vehicle are attached in place on an automobile that it is extremely difficult 20 for one to enter or attain exit from the vehicle without unfastening the curtain which is disposed across the doorway and above the door; therefore the particular object of this invention is to obviate this trouble and consequent delay, and at the same 25 time permit a construction which will be neat and attractive in appearance, strong and durable in construction, and which can be manufactured and sold at a comparatively low price.

Other objects, in addition to those above mentioned, are to provide an extension for doors which will be easily attached in operative position, which is easily detachable 35 when not required, adapted to be rolled into a small compass of space that it may be stowed away, or which may be folded down against the inside of the door when not required in operative position.

40 Other minor objects and particular advantages of the invention will suggest themselves in the course of the following description, and that which is new will be correlated in the appended claim.

45 The preferred means for carrying out the principles of my invention in a practical manner is shown in the accompanying one sheet of drawings, in which—Figure 1 is an outside elevation of my invention in operative position in connection with a vehicle door. Fig. 2 is an inside view of the same, but taken on an enlarged scale from that of Fig. 1. Fig. 3 is an inside elevation of the upper portion of a door, showing the 50 socket-clips secured thereto. Fig. 4 is a perspective view of the frame of the extension.

Fig. 5 shows a fragment of the frame, partly in section showing the means for detachably connecting the side-arms and the horizontal upper bar. Fig. 6 is a front elevation of a 60 hinge for each of the side arms. Fig. 7 is the same as Fig. 6 but taken at right-angles thereto. And Fig. 8 shows the extension as folded down parallel with the inner face 65 of the door.

Similar indices denote like parts throughout the several views.

In order that the construction, the operation, and the advantages of my invention may be more fully understood and appreciated, I will now take up a detailed description thereof, in which I will set forth the invention as briefly and as comprehensively as I may.

In the drawings A denotes either one of 75 the two sides of the body of an automobile, in which there is a door opening which is adapted to be closed by the door B, the door being mounted by the hinges a and b, or in any other well known manner.

80 Letter C denotes the vehicle top. Detachable side curtains D and E close the space between the body A and the top C, except that directly above the door B.

The invention proper comprises the two 85 socket-clips 1 and 2, which are secured to the inner face of the door, near the upper edge thereof and parallel with each other, each being attached by a pair of screws, as the screws 3 and 4, respectively. The said 90 socket-clips are the only parts of the invention which are permanently attached to the vehicle, and even these are very easily removed and as easily attached in place.

The frame, shown in Fig. 4, comprises 95 the side arms 5 and 6, which are disposed vertically and parallel with each other, the lower portions of said arms being bent or offset inward and they then extend downward forming the two pintles 7 and 8, respectively, which pintles are formed parallel with the side arms 5 and 6, the offset portions 9 and 10 are disposed at angles such as to meet various conditions. The arms 5 and 6 are placed the same distance 100 apart as are the clips 1 and 2, and the pintles 7 and 8 are adapted to fit and to slide down into the upper ends of said clips, as shown in Fig. 2. The horizontal member 11 of the frame has each end thereof bent 105 downward at right angles to the body thereof, to form the terminals 12 and 13, in each

of which is a socket to receive the reduced or flattened portions formed on the upper ends of the arms 5 and 6, as for instance the reduced portion 14 shown in Fig. 5, whereby 5 the member 11 is detachably connected to the arms 5 and 6. However, if desired, the arms 5 and 6 and the member 11 may be formed integral, or they may be otherwise connected as desired. In some instances the 10 arm 5 and the pintle 7 may be connected by a hinge 15; and in like manner the arm 6 and the pintle 8 may be connected by a hinge 16, or these parts may be made integral with each other as shown in Fig. 2. 15 If the hinges are employed they should be in or near the offsets 9 and 10.

Numeral 17 denotes a section of fabric, preferably doubled, forming the body or main portion of the extension, whose width 20 is slightly more than the width of the door B, in order that it may lap over or under the side curtains D and E, and the length of said fabric extension is such as to extend down and lap out over the upper edge of the 25 door B and to extend up inside of the lower edge of the top C. One or more transparencies 18 may be placed in the fabric 17 in order to provide light or a clear vision to one inside the vehicle.

30 The frame shown in Fig. 4 is located between the two thicknesses of the fabric of the extension, and it extends around the transparency 18, and it is secured in place by stitching the two thicknesses of fabric together around and near to both sides of each 35 member of the frame, except the pintles 7 and 8 which project down below the fabric as shown.

We will suppose, for instance, that the 40 device be assembled and in operative position as in Figs. 1 and 2, it is evident that the extension and the door will completely fill the door-opening, yet if the door be opened it is evident that the extension will open 45 therewith thereby providing an unobstructed full-length doorway for one to enter or to leave the interior of the vehicle.

If it be desired to provide ventilation 50 without opening the door then one has only to turn the extension inward and downward to the position in which it is shown in Fig. 8, thereby opening the upper portion of the doorway without opening the door.

If it be desired to dispense, temporarily, 55 with the extension then one has only to lift up on the entire extension and withdraw the pintles 7 and 8 from the clips 1 and 2, after which the arms 5 and 6 may be separated from the member 11, by pulling down on

the arms thereby withdrawing the reduced 60 portions 14 from the sockets in the terminals 12 and 13, and then withdrawing the arms from pockets formed by said stitching, after which the arms 5 and 6 may be laid over and parallel with the member 11 and the 65 fabric may then be rolled therearound whereby the device may be packed in a small compass of space until again required for use.

I desire that it be understood that various 70 changes may be made in the several details of construction from that herein shown, and in the arrangement of the several parts, without departing from the spirit of the invention and without sacrificing any of the 75 advantages thereof.

Having now fully shown and described the preferred means for carrying out the principles of my invention in a practical manner, what I claim and desire to secure 80 by Letters Patent of the United States, is—

In combination with a vehicle having a door opening and a door adapted to close the lower portion of the door opening, an extension carried by the upper portion of 85 the door and comprising in combination a section of fabric closing the door opening above said door and extending down outside the upper edge of the door and extending upward underneath the edge of the vehicle 90 top and adapted to be connected to the sides of the door opening, a frame formed of rods on which said fabric extension is mounted, there being pockets formed in the fabric for the members of the frame, the said frame 95 comprising two vertical side-arms and a horizontal upper section, means for detachably securing the upper ends of the side-arms to the ends of said horizontal section, socket clips secured to the inner face of the 100 upper portion of the door into which the lower ends of said side-arms of the frame are adapted to be detachably inserted and retained therein by gravity, hinges located intermediate said side-arms for providing 105 means whereby the extension may be turned down inside the vehicle and parallel with the door, the said extension being adapted to be disassembled and rolled into a small compass of space when not in use, all substantially as shown and described.

In testimony whereof I have hereunto subscribed my name to this specification in the presence of two subscribing witnesses.

EDWIN McGRAW.
